UNITED STATES PATENT OFFICE.

GEORGES ERNEST WAGNER, OF ST.-ETIENNE, FRANCE, ASSIGNOR TO SOCIETE ANONYME FRANCAISE DITE: SOCIETE ANONYME D'EXPLOITATION DES BREVETS GEORGEVITCH ET WAGEOR POUR DES MARTEAUX ROTATIFS MARGEOWA, OF ST.-ETIENNE, LOIRE, FRANCE.

ROTARY HAMMER.

Application filed January 30, 1928, Serial No. 250,828, and in France September 24, 1927.

Various kinds of rotary hammers operating by centrifugal force are known, comprising striking masses adapted to describe a rotary path by being carried on a rotary frame on the arms of which they slide radially, the rotary frame being actuated by a suitable mechanical transmission. These striking masses, in their rotary movement, are carried successively towards the centre 5 of rotation and are then left to themselves 10 of rotation and are then left to themselves at a predetermined point in their travel so that they can strike a tool on the head.

All such hammers and whatever the number of striking masses in play therein present 15 the serious defect of causing considerable vibration in the gear case, in consequence of the complete freedom allowed to each of the striking masses, from the moment when they move away from the centre until the moment 20 they strike on the anvil; furthermore, owing to the fact that rigid runways are employed, shocks are produced which are injurious to the performance of the apparatus and to the 25 preservation of their parts, when the striking masses, after having effected their work on the head of the tool, resume contact with the runway.

The present invention has for its object 30 improvements in the rotary hammers referred to, these improvements resulting in a considerable lessening of the vibrations and shocks due to the lack of equilibration produced by the movements of the striking 35 masses and the rigidity of the runways.

These improvements reside in the form and 40 nature of the runways.

In the accompanying drawings:—

Fig. 1 is a sectional view on the median 45 line of the runway of a hammer constructed in accordance with the invention;

Fig. 2 is a longitudinal section of the same 50 on the line II—II of Fig. 1.

As will be seen from the drawing, a frame 1 rotating in bearings 2 receives its rotary 55 movement from some outside source of energy (direct-coupled motor, flexible shafting, belt transmission, and the like). The rotary frame 3 is adapted to carry the striking masses 3, 3' which are diametrically opposed 60 and consist, in the embodiment shown, of cy-

lindrical rollers having trunnions 4 for their mounting.

The trunnions 4 are adapted to slide in 55 slots 5 provided in the forks of the arms of the frame 1.

The runway 6 is of such a predetermined 60 shape that it lifts the striking masses 3—3' during counter-clockwise rotation of the frame 1 through the angle B O A' and then imposes on them various paths of movements 65 as they come successively into contact with the anvil 7 on the end of the tool.

The shape of the runway is such that the 70 striking masses, in their travel, never leave the runway, except during the short interval 65 of the blow, i. e. during their displacement through the angle A O B.

It is known that the trajectory of each 75 striking mass, when free, is a definite one in space, independent of its weight and the angular velocity of its rotary frame.

Furthermore, it is to be noted that the 80 transmission of live power from each mass to the tool is effected over a slight amount of radial travel of this tool.

It is therefore essential that the bulk of 85 the apparatus should be subject to no displacement with respect to the anvil 7, at the risk of the capacity being considerably reduced.

If D O A is the angle of escapement of the 90 mass, i. e. the angle during which it moves away from the centre of rotation, the curvature of the runway, in this sector, will be substantially the enveloping curve of the 95 trajectory of the free mass, i. e. that it will be at least tangent to the enveloping curve, if not actually on the inside.

The curvature of the section of the runway 100 in the angle C O D may be concentric to the axis of rotation.

The curvature of the sector in the angle B O A', i. e. the curvature that produces the approach of the masses towards the centre of rotation may be either an arc of a circle, an 95 Archimedean spiral, or any curve.

At the moment of shock, the striking mass involved will leave the runway, i. e. during travel through the angle A O B.

In order to obtain a good equilibration, 100

even in the angle A O B, it is essential that the opposite striking mass should have, in the symmetrical sector A' O B', the possibility of following the trajectory which it would take if it was entirely free.

The runway, in this part, is therefore shaped to conform to the enveloping curve of the free trajectory of the mass in traveling through this angle.

10 Owing to this fact, there will be no recoil action on the bulk of the apparatus, i. e. no strain on the operator, or injurious action to the efficiency of the blow.

The part of the runway comprised in the angle B' O C will be of any suitable form, for connecting, without shock, the trajectory of the mass within the angle A' O B' to the trajectory which this mass must have within the angle C O D.

20 It should be pointed out that the equilibration of the rotary hammer system thus formed is not absolute, but that the lack of equilibration, resulting from the fact that, with respect to the vertical plane traversing

25 the axis of rotation, the striking mass or masses located at any moment nearest the anvil are always on a radius of gyration greater than that of the diametrically opposed mass or masses, has the effect of supplementing the effort made by the workman on the body of the hammer, for the purpose of maintaining contact with the work piece.

In order to prevent shocks from being produced in the rotary hammers when contact is resumed of the striking masses with the runway, the latter, in the region which receive the masses after the shock, is such that it forms a spring for receiving these masses and causes them to resume their trajectory

40 without any stop. To this end, the anvil 7, in its top position, projects slightly above the tip of the portion 8 of the runway. The end of the runway surrounds the end of the anvil on which the blow is imparted, and the mass,

45 while it is pushing forward said anvil, exerts a thrust on the resilient end 8 of the runway during the last portion of its run. The mass continues to roll on this extremity the resistance of which will be calculated according to
50 need.

To prevent all injurious vibrations in the portion 8, it may be made to bear against bearing-blocks 9, which may corporate with the runway or be independent thereof.

The end of runway 8 in its resilient portion 55 will of course not come in contact with the casing 10 enclosing the different elements of the hammer.

It is evident that the flexible portion 8 of the runway may be corporate with the latter, 60 as shown in the drawing, or may be inserted in the gear case in any suitable manner.

It will be understood that the method of carrying the invention into effect, which is shown in the accompanying drawing, is only 65 described by way of example and that modifications may be resorted to as regards the forms given to the runway, the number of the striking masses (the minimum number of the latter being two) and their displacement 70 on the rotary frame, which displacements may be effected either along a radius, or along a trajectory oblique with respect to a radius.

What I claim is:

1. A hammer comprising a rotatable 75 frame, masses carried by said frame and slideable radially therein under centrifugal force, a runway against which said masses bear except during the striking period, an anvil, that part of the runway immediately beyond the 80 tool head or anvil being resilient to cushion the contact of the striking masses therewith as they leave the said tool head or anvil, the end of the resilient part of the runway surrounding the anvil. 85

2. A hammer comprising a rotary mass-carrying frame comprising forked arms in which the masses can slide outwardly, an enclosing case, a tool head or anvil projecting inwardly through the case into the path of 90 said masses, and a runway shaped to control the radial movement of the masses throughout their path except just during the striking period and having the portion surrounding the anvil and the portion just beyond the tool 95 head or anvil resilient, substantially as and for the purposes specified.

In testimony whereof he has signed his name to this specification.

GEORGES ERNEST WAGNER.
